(57) **CLAIM**

The ornamental design for a portable power station, as
shown and described.

DESCRIPTION

FIG. 1 is a front view of a portable power station showing
our new design;

FIG. 2 is a rear view thereof;

FIG. 3 is a left-side view thereof;

FIG. 4 is a right-side view thereof;

FIG. 5 is a top view thereof;

FIG. 6 is a bottom view thereof; and,

FIG. 7 is a front, left perspective view thereof.

The use of stippling and shading is provided to show
contrast in materials and/or to differentiate between different
areas of the design.

Broken lines used in the drawings show unclaimed portions
of the portable power station.
